No. 748,713.

PATENTED JAN. 5, 1904.

W. FEHR.
HEDDLE.

APPLICATION FILED SEPT. 18, 1903.

NO MODEL.

UNITED STATES PATENT OFFICE.

WILLIAM FEHR, OF PHILADELPHIA, PENNSYLVANIA.

HEDDLE.

SPECIFICATION forming part of Letters Patent No. 748,713, dated January 5, 1904.

Application filed September 18, 1903. Serial No. 173,655. (No model.)

To all whom it may concern:

Be it known that I, WILLIAM FEHR, a citizen of the United States, residing at the city of Philadelphia, in the county of Philadelphia 5 and State of Pennsylvania, have invented certain new and useful Improvements in Heddles, of which the following is a specification.

My invention has relation to a heddle formed of thin flat metal, preferably steel, 10 and in such connection it relates to the arrangement and construction of the heddle.

In heddles of the present type the band or strip of metal is provided at either end with a slot or mortise to permit the heddles to 15 slide back and forth on the cross-rod of the heddle-frame, and it is also provided centrally with a slot or eye, through which the warp-thread is passed when the heddle and its frame are in operative position in the 20 loom. The formation of the end and central slots in thin, flat, and narrow strips of metal—steel, for instance—renders the heddle weak and liable to break at these points. Many ways of forming these slots have been 25 devised; but the disadvantage of weakness has not heretofore been successfully avoided.

The principal object of my present invention is to provide a heddle consisting of a thin flat narrow strip of metal having end 30 mortises and a central eye formed by slitting the strip at these points and then expanding the metal by a swaging or similar operation to form an opening in the swaged portion of the metal, the bearing surface or surfaces of 35 the opening being thereby protected or reinforced by a fin or fins formed by the swaging down of the metal adjacent to said bearing-surface.

The nature and scope of my present invention will be more fully understood from the 40 following description, taken in connection with the accompanying drawings, forming part hereof, in which—

Figure 1 is a front elevational view of a 45 heddle embodying main features of my invention. Fig. 2 is an enlarged front elevational view of the upper slot or mortise of the heddle. Fig. 3 is a vertical sectional view of Fig. 2. Fig. 4 is an enlarged front elevational view of the intermediate slot or eye of

the heddle; and Fig. 5 is a view corresponding to Fig. 2, but illustrating a modified form of end slot or mortise for the heddle.

Referring to the drawings, *a* represents a thin flat strip or narrow band of metal, preferably steel, and having at either extremity a mortise or slot *b* and intermediate of the extremities the slot or eye *d* of the heddle. In the form of end mortise *b* (illustrated in Figs. 1 to 3, inclusive) the opening or slot 55 constituting the mortise is formed in the following preferred manner: The band *a* is first slit, as indicated in dotted lines at *a'* in Fig. 2, and thereafter the metal surrounding the slit *a'* is subjected to a swaging or similar 60 operation to flatten the metal and to expand the slit *a'* into the slot or opening *b*, constituting the mortise. When so formed, the mortise *b* has an upper and a lower bearing-surface *b'*, formed of a thin fin of swaged 65 metal, which reinforces the ends of the mortise *b* and prevents breakage of the heddle at the mortised extremities.

In Fig. 5 a modified form of end mortise *b*¹⁰ is illustrated, in which the reinforcing-fin *b*¹¹ is formed only adjacent to the upper bearing-surface of the mortise during the swaging or similar operation.

The intermediate eye *d* of the heddle is preferably formed by slitting the metal *a* at 70 the point where the eye is to be formed and in thereafter subjecting the metal surrounding the slit to a swaging or similar operation to flatten the metal and expand the slit into a substantially rectangular opening or eye 75 *d*, the perimeter of which is surrounded by an elliptical frame *d'*, of swaged metal, forming a reinforcing-fin for all bearing-surfaces of the eye-opening.

It should be understood that instead of 80 first forming the slits for the end mortises or intermediate eye in the metal and thereafter swaging the metal surrounding the slits to form the slots or eye the metal may first be expanded by the swaging or similar operation and thereafter the slots and eye cut into the swaged portions of the band without departing from the spirit of my present invention.

Having thus described the nature and ob- 90

jects of my invention, what I claim as new, and desire to secure by Letters Patent, is—

1. A heddle, consisting of a thin, flat narrow strip of metal provided at either extremity with a mortise or slot having a bearing-surface reinforced by a thin fin of swaged metal.

2. A heddle, consisting of a thin, flat narrow strip of metal having intermediate of its

ends an eye surrounded by a thin fin of swaged metal.

In testimony whereof I have hereunto set my signature in the presence of two subscribing witnesses.

WILLIAM FEHR.
